CONTINUOUS VULCANIZER

Fred B. De Haan, Paterson, N.J., assignor to The Okonite Company, Passaic, N.J., a corporation of New Jersey

Application April 24, 1957, Serial No. 654,760

2 Claims. (Cl. 18—6)

My invention relates to an improvement in vulcanizers of the continuous type wherein the vulcanizable covers of articles, such as electric wires and cables, may be continuously vulcanized.

One of the objects of my invention is to provide a construction whereby the wire or cable may be introduced into the vulcanizing tube and continuously discharged therefrom in a more satisfactory fashion than possible with existing conventional equipment.

In general, my improved vulcanizer comprises a long, cylindrical tube, eighty or more feet in length. Dry steam is admitted to this tube intermediate its ends and prevented from escaping at the tube ends by a water seal. The wire or cable to which the cover to be vulcanized has already been applied is continuously advanced through the tube. The steam is maintained at a pressure of one hundred pounds per square inch, or higher, and the interior of the tube is raised to a temperature of around 330° F. Thus, by regulating the rate at which the covered wire or cable is advanced through the tube, the exposure to curing temperature and, consequently, the degree of vulcanization can be controlled.

Prior to my invention a definite problem existed with respect to the introduction of the wire or cable into the vulcanizing tube and its discharge from the exit end of the tube. Normally, a metal plate is emplaced over the tube ends to retain the water seals inside the tube. As the wire or cable is drawn through the tube, this plate must be withdrawn to allow the wire or cable to pass out of the tube. The wire or cable fits into a circular opening at the tube ends, thus preventing the escape of water. However, in the short interval of time between the removal of the plate and the entry of the cable into the circular opening, the steam pressure is acting upon one end of the water seal, while the other end of the seal is at atmospheric pressure. This creates an unbalance in the system and a consequent temperature drop. This has an unfavorable effect upon the curing of the covering of the wire or cable, since some time must elapse before return to stable operation. The properties displayed by the covering being vulcanized will vary accordingly, and an unsatisfactory product results.

My invention provides against such conditions and embodies a construction whereby the covered wire or cable enters into and exits from the vulcanizing tube without detrimental loss of water and without disrupting the balanced conditions existing within the vulcanizing tube; the only water which is allowed to escape is a very slight amount just about the wire or cable which functions as a lubricant.

In the accompanying drawings, wherein I have illustrated an embodiment of my invention,

Fig. 1 is a sectional view taken at the discharge end of my improved vulcanizer; and

Fig. 2 is an elevational view of the vulcanizer.

Referring to the drawings in detail, 2 designates a vulcanizing tube, which is a long, cylindrical tube, eighty feet in length, for example, and, say, eight inches internal

2

diameter. These dimensions are purely by way of illustration.

Provision is made about midway of the length of the vulcanizing tube, as illustrated at 4, for admitting dry steam to the tube interior. This steam may be at a pressure of the order of one hundred pounds per square inch. Adjacent each end of the tube 2 means are provided, designated 6, for admitting water under pressure from any suitable source to the tube interior at each end of the steam charge, thereby to provide a water seal for the steam.

8 designates a steel housing at each end of the vulcanizing tube 2, this housing acting as a holder for an aluminum bushing 10 (see Fig. 1). Each bushing is held in place by a steel retaining ring 12. The ring is held in place by cap screws 14, which pass into the housing 8 through keyhole slots in the ring to permit the ring to be removed without the necessity of removing the screws. Each of the housings 8 is provided with an internal annular groove 11, and lying within each of these grooves is an inflated ring gasket 13 for preventing the escape of water along the exterior of the bushing.

Each of the rings 12 is provided with an extension tube 16. Each tube fits into its ring and projects fifteen inches, more or less, beyond the outer face of the ring. Each extension tube is provided at its outer end with a cover plate 18, provided with a radial slot 20. Each cover plate is carried by an arm 22, fulcrumed at 24, and operated from an air cylinder 26.

Immediately back of each of the bushings 10 are sealing diaphragms 28. These are of neoprene; for example, and act as water guards and provide for some variation in wire or cable outside diameter. A film of water is allowed to flow between the diaphragms and the wire or cable, to lubricate the wire or cable and to avoid chafing. Within each housing 8, between an internal shoulder 9, with which each housing is provided, and the sealing diaphragms 28, is a belled steel ring 30, which rings prevent displacement of the diaphragms and facilitate entry of the wire or cable.

The wire or cable the cover of which is to be vulcanized has been designated 32. Fig. 1 is taken at the discharge end of the vulcanizer, and it will be seen from this view that the leading end of the wire or cable is equipped with 45 a pulling eye 34, to which is attached a pulling line 36. In commercial operation the wire or cable will be drawn through the vulcanizer from a let-off reel at one end of the vulcanizer and, after passing through the vulcanizer, will be rewound upon a take-up reel at the discharge end 50 of the vulcanizer.

In operation, the pulling line 36 is first threaded through the vulcanizer until its leading end projects from the outer end of the extension tube 16 at the discharge end of the vulcanizer. The slot 20 permits the cover plates 55 at each end of the vulcanizer to be closed at that time. The pulling line is drawn through the vulcanizer until the leading end of the wire or cable 32 enters the seal at the entry end of the vulcanizing tube 2, the plate 18 at the entry end of the vulcanizer being raised to permit 60 passage of the wire or cable. With the steam and water on in the vulcanizing tube, the wire or cable is drawn through the tube until the leading end of the wire or cable has entered the seal at the exit end of the vulcanizing tube, as illustrated in Fig. 1. During the passage of the wire 65 or cable to this position, the cover plate at the discharge end of the vulcanizer is kept closed; hence, no water can escape at this end of the vulcanizer to a detrimental extent. Water is prevented from escaping at the entry end of the vulcanizing tube by the diaphragms 28. When the 70 wire or cable reaches the position illustrated in Fig. 1, then the cover plate 18 at the exit end of the vulcanizer can be opened to permit the wire or cable to pass through

the extension tube 16 at that end of the vulcanizer. As the leading end of the wire or cable emerges from the exit extension tube 16, the pulling line 36 is removed, and the end of the wire or cable is made fast to the take-up reel. The trailing end of the wire or cable is equipped with a light line, which is used to draw the pulling line back through the vulcanizer as each length of wire or cable has been vulcanized, so that the pulling line may be attached to the next length which is to be drawn through the vulcanizer.

It will be seen from the foregoing that with my improved apparatus provision is made for vulcanizing the entire length of wire or cable in that, from the time the leading end of a length enters the seal at the entry end of the vulcanizer until the trailing end of the length is discharged, the vulcanizer is sealed against detrimental loss of water, and disruption of equilibrium of the system is avoided, so that uniformity of cure is assured.

It is to be understood that changes may be made in the details of construction and arrangement of parts hereinabove described within the purview of my invention.

What I claim is:

1. A vulcanizer for the continuous vulcanizing of the covering of long lengths of electric cable, said vulcanizer comprising, in combination, an elongated, cylindrical tube; means for supplying dry steam to the tube interior intermediate the tube ends; means for supplying water to the tube interior adjacent each end of the tube, thereby to provide a water seal for the said steam; sealing means at each end of the tube positioned to cooperate with the cable being vulcanized, as the cable advances through the tube, for sealing the tube ends against deleterious water leakage from the tube; an extension tube on each end of the main tube; a cover plate for the outer end of each of said extension tubes provided with an opening for the passage of a pulling line by which the cable is initially advanced through the vulcanizing tube, said cover

5 plates preventing the escape of water from the apparatus to a deleterious extent until the cable has been advanced sufficiently to have entered the said sealing means at the tube ends, the sealing means co-acting with the cable thereafter to continue the sealing action.

2. A vulcanizer for the continuous vulcanizing of the vulcanizable covering of electric wires and cables, said vulcanizer comprising, in combination, an elongated, cylindrical tube through which the article to be vulcanized is continuously advanced; means for supplying dry steam to the tube intermediate the tube ends; means for supplying water to the tube interior adjacent each end of the tube to provide a water seal for the steam; a housing affixed to each end of the tube; a metal bushing set into each of said housings, the bore of each bushing being in alignment with said tube; a ring for holding each of said bushings in place in the housing; an extension tube at each ring coaxial with the first-mentioned tube, one end of each of said extension tubes abutting the inner peripheral surface of a ring, the remaining portion of each extension tube extending beyond the plane of the ring; a cover plate at the outer end of each of said extension tubes; a flexible, plastic ring mounted in each of said housings at the inner face of said bushings, the inner diameter of said rings being substantially the same as the outer diameter of the wire or cable; and an inflatable ring gasket surrounding each of said bushings for preventing the escape of water from the tube along the exterior of the bushings as the wire or cable is being advanced through the apparatus.
